UNITED STATES PATENT OFFICE.

LUCIUS J. PHELPS, OF NEW YORK, N. Y., ASSIGNOR TO THE RAILWAY TELEGRAPH COMPANY.

RAILWAY TELEGRAPHY.

SPECIFICATION forming part of Letters Patent No. 355,470, dated January 4, 1887.

Application filed July 3, 1886. Serial No. 207,007. (No model.)

To all whom it may concern:

Be it known that I, LUCIUS J. PHELPS, a citizen of the United States, and a resident of New York, in the county of New York and State of New York, have invented certain new and useful Improvements in Railway Telegraphy, of which the following is a specification.

The object of my invention is to provide a means for maintaining telegraphic communication with a moving vehicle—such, for instance, as a railway-car—whether in motion or at rest, over the same telegraph-line on which are located stations provided with ordinary telegraph apparatus of any kind—such, for instance, as Morse telegraph apparatus—with out interference with or from the simultaneous use of the line for the purpose of telegraphing by the Morse or similar apparatus.

In carrying out my invention I propose to use suitable means for telegraphing to the train by what I sometimes term "vibration signals"—that is to say, signals whose elementary portions consist of a series of electrical pulsations, vibrations, or undulations coming, preferably, with a rapidity sufficient to produce the sensation of a musical tone.

In a system of Morse telegraphy in which vibration-signals are employed the dots and dashes may be represented, respectively, by musical sounds of a duration corresponding to the length of the dots and dashes.

My present invention has reference more especially to a system in which the telegraphing to the train may be carried on by vibration-signals without interfering with the use of the line simultaneously for the purpose of telegraphing by ordinary Morse or other apparatus connected directly into the telegraphic circuit.

Among other things, my invention relates to a means for setting up the electrical vibrations on the telegraph-circuit, from which they are inductively transferred to the vehicle by means of devices—such, for instance, as those described in my prior Patents Nos. 312,506 and 334,187—to be read or received on said vehicle on an ordinary telephone-receiver or other instrument responsive to such vibrations.

In the present instance I have shown my invention as carried out by means of a conductor

mounted upon a vehicle in parallelism to the Morse telegraph circuit or line, and connected on the vehicle with the receiving and transmitting apparatus. I do not, however, limit myself to such special devices, since the same results may be effected by the employment of any arrangement that will give an inductive connection between the vehicle and the line without actual contact.

My invention consists in the combination, with an electro-magnet having connections to the circuit, of a vibrator or commutator whereby the coils of said magnet may be intermittently included in circuit with a suitable source of electricity and a telegraph-transmitter, all combined so that the extra or secondary currents developed in the coil of the magnet when the circuit through said coils and the generator is broken by the vibrator may be controlled by the key, and may act as the electrical pulsations, or vibrations by which vibration-signals are transmitted.

My invention consists, further, in the combination, with the telegraph-line having Morse apparatus thereon or other suitable telegraph apparatus shunted by condensers, of an electro-magnet whose coils are connected to the line, a rheotome or vibrator in a branch around said magnet, a generator of electricity whose current is caused to flow intermittently in the coils by means of the rheotome or vibrator, and a key or transmitter for controlling the flow to line of the extra or secondary currents set up by the interruption of the circuit of the generator through the coils.

My invention consists, also, in certain details and combinations of apparatus, that will be described in connection with the accompanying drawings, and then more specifically recited in the claims.

Figure 1 is a diagram of apparatus arranged and combined in accordance with my invention. Fig. 2 illustrates the application of the invention to a wire where it is desired to use only a portion of the same for train telegraphing. Fig. 3 illustrates a modification in the arrangement of the key, telephone-receiver, and electro-magnet, the extra currents from which are employed as the electric vibrations for telegraphing to the train. Fig. 4 illustrates a form of rheotome or vibrator that may

be used in place of that shown in the other figures. Fig. 5 illustrates a modification.

Referring to Fig. 1, L indicates a telegraph-line, including two or more stations, A B D, &c. At the stations B D are located telegraph apparatus of any suitable character, included in the line-circuit and normally shunted by condensers C, which serve to preserve the circuit for vibration-signals when the line-circuit is interrupted by the operation of the transmitters at said stations. In the present case I have shown the stations as provided with ordinary Morse telegraph apparatus, consisting of relays R and Morse keys K. The battery which charges the line-wire L during communication between stations by the employment of the Morse telegraph apparatus is indicated at M B.

A railway car or vehicle (indicated at E) is provided with a conductor carried parallel to the telegraph-line L, and in suitable inductive proximity thereto, as described in my prior Patent, No. 312,506, before referred to. On the vehicle is located suitable apparatus for receiving vibration-signals transmitted from a station, A, over the line L, and inductively transferred to the vehicle. Similar apparatus to that employed at the station A may be employed in telegraphing from the vehicle to the station, though in the present instance I have shown a simple form of device for setting up vibration-signals on the car-circuit, to be transferred inductively to the line, and composed, essentially, of a generator of electricity, L B, a vibrator, V, consisting of an electro-magnet whose armature and coils are included in the circuit of the generator, and a transmitter or key, K, which controls the passage of the interrupted currents of the generator over the car-circuit. The vibration-signals are received on the car by means of an ordinary speaking-telephone receiver, T, or other instrument which is sensitive or responsive to the electrical vibrations sent from the station A, and inductively transferred to the vehicle. Other devices might be used in place of those described without departing from the invention. The station A contains the vibration signal apparatus.

In the circuit of the line L is shown an electro-magnet, M, consisting of a bundle of fine iron wire wound with a continuous coil of coarse wire. The current from the generator of electricity a, consisting of a galvanic battery or other device, can be made to flow intermittently through the coils of the magnet by means of a vibrator or rheotome consisting in the present instance of the armature-lever H for the electro-magnet that when against its back stop completes a shunt or branch circuit through which the current of the generator may flow. When the armature is drawn up by the flow of current, the shunt or branch is interrupted, and the extra current of the coils flows over the line. For the purpose of controlling the flow of such extra current, the transmitting-key K may be placed in the shunt

with the rheotome or vibrator, as indicated, so that when the key is closed the shunt is completed, and the vibrator will then have a circuit through the coils and generators. When the key is closed, the rheotome vibrates automatically, being drawn forward when the circuit of the magnet is completed through the contact against which the rheotome rests when out of action, and being thrown in the opposite direction by its spring when by the attraction of the magnet the magnet's circuit is broken. It will thus be seen that the rapid vibrations of the rheotome will produce rapid breaks and make of circuit through the magnet, which will continue as long as the key is closed, and will result in throwing upon the line a series of extra currents from the magnet, each one of said series passing the line on the interruption of the local circuit at the vibrator-contact. By this means, and by the operation of the key, Morse signals may be sent, each character of the Morse signal being represented by a series of vibrations of greater or less duration, according to the time that the key remains depressed. When the key is open, the vibrator cannot work, because its circuit through the magnet is open. Any other form of rheotome or vibrator adapted to rapidly interrupt the flow of current of the generator through the coils of A might be employed—as, for instance, a clock-work rheotome of the ordinary well-known form illustrated in Fig. 4.

The receiver for vibration-signals coming from the vehicle may consist of an ordinary telephone, T, placed in a branch to earth from the back contact of the key K, which branch also includes a condenser, C, whose function is to prevent the battery a from being short-circuited to ground.

In order to prevent the charge and discharge of the condenser C from affecting the telephone, I make the back contact of the key K in the form of a spring, f, which, when the key is depressed, makes connection with a stop, b, connected to the same pole of the condenser with the telephone.

In the position of the devices shown in Fig. 1, which is supposed to be their normal position, the line L is complete through the apparatus at the stations B and D, and messages may be sent and received over the line by the employment of such apparatus in the ordinary way. The condensers C serve the function of also preventing the otherwise sudden changes of tension which would take place on the circuit from the opening and closing of the keys K by acting as graduators to cause the current to gradually rise and fall from its maximum to its minimum tension. By this means the disturbing effects upon the telephone-receivers at station A and upon the vehicle are greatly reduced.

The operator upon the vehicle E communicates with the operator at station A by using his key, so as to establish vibration-currents on the vehicle-circuit, which, being induct-

5 ively transferred to the line L, flow to a telephone, T, at station A. Such vibration-signals find circuit through the condenser C², and, in case the keys K at the Morse telegraph-sta-
tions are open, are inductively transferred from one section of line to the other by means of condenser C. When the key K is depressed, the branch from line containing the telephone and condenser is disconnected, and at the same 10 time a local circuit is formed, including the coils of the electro-magnet M, the generator a, the contacts of the vibrator, and the front stop of the key. So long as the key remains depressed this circuit is rapidly made and interrupted, and at every interruption the extra current from the coils of the electro-magnet flows over the line-circuit, thus giving the vibratory or pulsatory current, which, being inductively transferred to the vehicle, produces 15 vibration-signals in the telephone-receiver thereon.

20 In Fig. 2 I have illustrated an arrangement that may be employed where it is desired to use a portion only of the line—as, for instance, the section 2 for vibration signals—and to cut off the section 3 from any effects of such vibration-signals. In this instance the generator a is not in the line-connection controlled by the key K. The coils of electro-magnet M are 25 placed in the line-circuit, as indicated; but on the side of said coils remote from section 2 a branch to earth is made through a large con-
30 denser, C², which serves to cut off the pulsations or vibrations originating in the electro-
magnet from the section of line 3. The tele-
35 phone-receiver T at station A, for the vibration-signaling apparatus, is connected, as in Fig. 1, in a branch from the back contact of the key to earth, including a condenser, C².
40 The apparatus is used in all respects in the same way as the apparatus in Fig. 1. It will be seen, however, that in this arrangement when the flow of current of the generator through the coils is interrupted such generator 45 is not in the circuit over which the extra or secondary current from the coils flows.

45 In the arrangement of devices shown in Figs. 1 and 2 it will be seen that there is an opportunity for the electrical vibrations coming over the line to pass in part to earth, avoiding the telephone-receiver T when the key is against its back stop. This difficulty can be avoided by the employment of suitable switches when the operator at station A is receiving a mes-
50 sage; but when he is transmitting a message and the operator on the vehicle desires to "break" him, the telephone will not be affected to its fullest extent by the electrical vibrations induced on the line from the vehicle, inasmuch as a part may escape to earth through the coils a and the condenser C², which in this case has the same function as the condenser C² in Fig. 1.

55 By the arrangement of devices shown in Fig. 3 I avoid this defect, and force all the vibration-currents to pass through the telephone when the key is on its back contact. This I do by the employment of a continuity-preserv-

60 ing key having two stops or contacts, one of which, when the key is open, closes the line-circuit through the telephone, while the other, 70 when the key is depressed, completes the circuit through the coils of the extra-current electro-magnet. These contacts are so arranged that circuit through either shall be made before contact at the other is broken. In 75 the depressed position of the key the circuit of a local generator through the coils of the magnet and the rheotome is made, while at the same time the circuit for the line directly through the coils of the electro-magnet is pre- 80 served.

The key K is of any suitable mechanical construction, and is arranged so as when depressed to make connection with a spring or lever, m, connected to line and normally resting against 85 a stop connected to a branch containing the telephone-receiver T.

The key K is connected through the coils of M with a continuation of the line. When the key is in the position shown, the line is complete through the telephone T; but when the key is depressed the line is completed through the coils of the electro-magnet at the same time or the instant before the branch containing the telephone is broken. When the key is fully 95 depressed, connection of the lever m with a stop, o, is made, which stop connects with the branch or shunt circuit, including the generator a and the contacts of the vibrator, so that 100 circuit is completed through the coils of M and the key K for the vibrator and generator. In the latter position of the key it will be observed that the circuit for the line is still intact through the coils of M, so that at every interruption of the circuit of the generator 105 through said coils, produced by the rheotome or vibrator, the extra current of the coils will flow over the line. Other forms of continuity-preserving keys might be used for the same purpose. 110

115 It is not necessary that the coils of the electro-magnet M should be in the direct line-circuit. Its coils may have inductive connection with the line—as, for instance, by a condenser, C², Fig. 5, which serves to transfer the extra-current vibrations of the magnet to the line in obvious manner.

120 What I claim as my invention is—

1. The combination, with the electro-magnet M, of a generator of electricity and a vi- 120 brator or rheotome for producing rapid inter-
ruptions of the flow of current of the generator through the coils, a transmitting-key, and di-
rect connections from the coils of the magnet 125 to a telegraph-circuit, so that the coils shall be in the direct telegraph-circuit, as and for the purpose described.

130 2. The combination, in a vibration-signal apparatus, of an electro-magnet having its coils connected in the direct circuit of the line or portion of line on which electrical vibrations are to be produced, a branch circuit around said coils, including a vibrator or rheo- 135 tome for producing rapid interruptions of cur-

rent flow in the coils, an armature for the magnet carried by the vibrator, and a key or transmitter, as and for the purpose described.

3. The combination, in a vibration-signal apparatus, of an electro-magnet having its coils in the direct line-circuit, an armature for said magnet controlling a branch around the same, and a transmitting-key, as and for the purpose described.

10 4. The combination, with a telegraph-line, L, having two or more stations provided with telegraph apparatus connected into the circuit of the line and shunted by condensers, of an electro-magnet having its coils included directly in the line-circuit, and a vibrator or rheotome for completing a branch around said magnet, through which a current from a suitable generator may circulate intermittently in a path including the coils.

15 5. The combination, with a Morse telegraph-line, having Morse apparatus shunted by condensers, of a vehicle provided with means whereby signals may be received and transmitted by induction to and from the line, and 20 a station connected to the line-circuit and provided with an electro-magnet whose coils are connected directly to line; a vibrator or rheotome controlling the circuit of a generator of electricity through the coils, and a transmitting-key.

30 6. The combination, with the line-circuit L, of an electro-magnet in the direct circuit of the line, a rheotome or vibrator, and a key for completing the circuit of a generator of 35 electricity through the coils, said circuit including the rheotome, the contacts of the key, and a branch of the main circuit around the coils.

7. The combination of a telegraph-line 40 stretched parallel to the path of a vehicle, induction apparatus whereby vibration-signals on the line may be inductively transferred to a circuit or connection on the vehicle, a telephone for receiving the vibration-signals, and 45 at a station connected with the line-circuit an electro-magnet in the direct line-circuit, and a vibrator or rheotome for intermittently com-

pleting the circuit of a generator of electricity through the coils of said electro-magnet, whereby electrical pulsations or vibrations may be produced through the extra or secondary currents developed in said coils.

5 8. The combination, with the transmitting-key K and the telephone and condenser in a branch from the back contact thereof, of a supplemental connection from the same pole of a condenser to which the telephone is connected, whereby the charge and discharge of the condenser may be prevented from passing through the telephone.

60 9. The combination, with the continuity-preserving key, of an alternating current source consisting of a magnet in a connection from one stop of said key, in combination with a vibrator for causing pulsations of a battery-current in the magnet-coils, and a telephone in a connection from the normal or back stop of said key, as and for the purpose described.

10 10. The combination, with the line L, of a transmitter controlling three branches of the line, one containing a telephone-receiver, the other the coils of an electro-magnet, and the third a generator and contacts of a rheotome or vibrator, as and for the purpose described.

70 11. The combination, with a Morse telegraph-line having its Morse apparatus shunted by condensers, of a vehicle carrying transmitting and receiving apparatus operating to transmit and receive signals by inductive transfer to and from the line, an electro-magnet 75 having coils connected to the line, a vibrator or rheotome controlling the flow of current of a generator of electricity through the coils, and a key for controlling the secondary or extra currents produced by the action of the vibrator.

80 Signed at New York, in the county of New York and State of New York, this 2d day of July, A. D. 1886.
